(57) **CLAIM**

The ornamental design for a cartridge for a dry powder inhaler, as shown and described.

DESCRIPTION

FIG. 1 is a perspective view of our new cartridge for a dry powder inhaler design.

FIG. 2 is a top view of the cartridge for a dry powder inhaler shown in FIG. 1.

FIG. 3 is a bottom view of the cartridge for a dry powder inhaler shown in FIG. 1.

FIG. 4 is a back view of the cartridge for a dry powder inhaler shown in FIG. 1.

FIG. 5 is a front view of the cartridge for a dry powder inhaler shown in FIG. 1; and,

FIG. 6 is a side view of the cartridge for a dry powder inhaler shown in FIG. 1.

The broken lines in FIGS. 1-4 represent the portions of the cartridge, which form no part of the claimed design.
